Attorney.

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING-MACHINE.

1,368,299.

Specification of Letters Patent. Patented Feb. 15, 1921.

Application filed June 18, 1919. Serial No. 305,169.

To all whom it may concern:

Be it known that I, JESSE A. B. SMITH, a citizen of the United States, residing in Stamford, in the county of Fairfield and 5 State of Connecticut, have invented certain new and useful Improvements in Typewriting-Machines, of which the following is a specification.

This invention relates to typewriting machines, and is herein described as applied to the Underwood standard typewriting machine. In using such machines for making out bills, it becomes exceedingly important if the work is to be done economically, 15 that the typist be able to rapidly and accurately adjust both a bill or memorandum and a record sheet in the machine. Moreover, since record sheets are likely to have a number of their lines already written 20 upon, it becomes important to provide means whereby the record sheet may be rapidly and accurately brought to the printing point at any one of a large number of writing lines, while the memorandum or 25 bill head should always have the same line brought to the printing point.

Where a great many entries are to be made, one or two entries at a time upon short bill heads, the time occupied in inserting the multiplicity of bills and record sheets into the machine and removing them therefrom materially cuts down the economy effected by using a typewriting machine for this work. According to the present invention, the typewriting machine may 35 be provided with a table above the printing point, adapted to receive the record sheet when passed around the platen in the usual way, thus enabling the record sheet to be adjusted by or impaled upon a pin or 40 pair of pins, which serve to aline it and are at a certain number of line-spaces from the printing point. When thus alined, the record sheet may be freed from its pin or 45 pins, and the bill head or memorandum sheet may be dropped down between the record sheet and the platen against the bite of the front feed rolls, which thus serve as a bottom end gage. If the bill head is of 50 the right size and the front feed roll is at the proper distance from the pins, the desired writing line upon the bill head is in alinement with the next line upon the record sheet which is to be written upon. Then 55 a backward turn of the platen brings the

proper line of the record sheet and bill head to the printing point, whereupon the writing may proceed.

In this manipulation of a bill head, it will be seen that the record sheet is used 60 as a front insertion guide; and to enable this to be done, the platen is so positioned as to stand clear of the usual wing scales and other paper-guiding mechanism which might serve to arrest the bill head while being inserted.

Other features and advantages will hereinafter appear.

In the accompanying drawings,

Figure 1 is a perspective view of an Underwood typewriting machine shift-frame, with many parts omitted, showing my invention applied thereto; there being also shown a few parts adjacent the shift-frame.

Fig. 2 is a sectional side view, largely diagrammatic, showing the record sheet passed around the platen.

Fig. 3 is a similar view, showing the record sheet held against the platen by the feed-rolls and the bill head inserted behind 80 the record sheet.

Fig. 4 is a similar view, showing the pins withdrawn and a type-bar in the act of printing upon the work-sheet.

Fig. 5 is a perspective view of a pin and 85 the means for releasing it.

In the usual Underwood typewriting machine, the platen 10 is journaled in the ends 11 of a shift-frame, which also includes a rear paper-table 12 joining the ends 11. 90 The platen is adapted to be turned in the usual manner either by a knob 13 or by the line-space mechanism, which includes a line-space lever 14, a pawl-carrying slide 15 and a line-space wheel 16, which is fast to the 95 platen. In order to detain the platen at any position to which it is turned, there is provided the usual detent 17 pressed by a spring 18 against the line-space wheel 16.

According to the present invention, if a 100 record sheet 19 is passed around the platen by inserting it over the paper-table 12, it is guided by a lower extension 20 of said paper-table past the rear feed rolls 21 and the front feed rolls 22, and then swung upward, being deflected by the usual wing scales 23, which stand close to but clear of the platen and any work-sheet passed around it. When the record sheet is thus inserted, the typist advances it with the 110

feed rolls cast off as in Fig. 2, and impales it by two of its openings 24 upon a pair of pins 25 and 26. These pins, as herein-after described, serve also as an indicating device for indicating the point at which the next line to be written upon should be positioned.

When the record sheet 19 is thus positioned, the feed rolls 21 and 22 may be 10 clamped against the platen by actuating the usual casting-off handle 27, which is connected by the usual link 28 to the usual shaft 29. The typist may now withdraw the pins 25 and 26 from the openings 24 15 by actuating a finger-piece 30, which is fast on the end of a shaft 31, thus causing cams 32 upon said shaft to cam rearwardly the springs 33 upon which pins 25 and 26 are fast, with the result that the pins are withdrawn 20 through openings 34 in a table 35. The table 35 is mounted on brackets 36 fast to the usual cover plates 37 of the shift frame, being held to the brackets by a front bar 38, which is fast to the table 35 and to 25 turned-over lugs 39 on the brackets 36. For convenience in use, the table may be wholly or largely above the level of the cover plates 37, and may extend upwardly above the pins 25 and 26 a considerable 30 distance, thus forming a flat extension 40, upon which the record sheet is adapted to be laid out flat, thus enabling it to be easily centered upon the pins 25 and 26, inasmuch as while it thus lies flat it does not 35 tend to spring clear of the pins. After the pins 25 and 26 have been withdrawn as described above, the end of the record sheet 19 may be drawn forward clear of the table and a bill head or memorandum 41, 40 together with an overlying carbon 42, may be dropped in behind the record sheet 19. Since the record sheet serves as a front guide for inserting the memorandum and carbon sheets, the latter drop downwardly 45 until they strike against the bite of the front feed rolls 22, which thus serve as a gage for them. There is nothing to arrest these sheets, since the wing scales, instead of holding the record sheet against the 50 platen, as would be the case in some machines, allow the bill head to pass freely. Moreover, the paper table and apron terminate at the front feed rolls, so that the bill head never reaches the point at which 55 the apron supports the record sheet.

The relative positions of the bite of the feed rolls 22 and the pins 25 and 26 are such that, when the bill head is thus gaged against the rolls 22, its first writing line 44 60 coincides with the writing line 45 upon the record sheet next to be printed upon. To enable the typist to see that the record sheet is properly positioned, there is provided an indicator to which the next writing line

may be set. This pointer is herein shown as 65 the pins 25 and 26 themselves.

To bring the writing lines 44 and 45 down to the printing point, the typist turns the platen backwardly by the knob 18; and since the pins 25 and 26 are an aliquot 70 number of line-spaces above the printing point, the detent 17 holds the platen with the record sheet and bill head so that their writing lines 44 and 45 are both at the printing point. The typist then writes the 75 line, and may actuate the line-space lever 14, to rotate the platen to bring the succeeding line or lines to be written upon to the printing point. When the writing is completed, the typist withdraws the record 80 sheet, bill head and carbon from the type-writing machine in the usual way.

Variations may be resorted to within the scope of the invention, and portions of the improvements may be used without others. 85

Having thus described my invention, I claim:

1. In a front-strike typewriting machine the combination with a revoluble platen, of a table above the printing point upon which a record sheet may be alined, disappearing pins at said table upon which openings at the writing lines of the record sheet are adapted to be centered, so that a selected writing line to receive the next printing is 90 an aliquot number of line-spaces above the printing point, a rear paper-table adapted to guide a work-sheet down beneath the platen, and feed rolls adapted to clamp the record sheet against the platen, and including a front feed roll in front of the rear paper-table so located with reference to the pins that the second sheet gaged against the bite of the front feed roll stands with its first writing line in alinement with the selected writing line of the record sheet. 100

2. In a front-strike typewriting machine, the combination with a revoluble platen, of a table above the printing point upon which a record sheet may be alined, a pair of disappearing pins mounted upon said table and upon which openings at the writing lines of the record sheet are adapted to be centered, so that a selected writing line to receive the next printing is an aliquot number of line-spaces above the printing point, a rear paper-table adapted to guide a work-sheet down beneath the platen, feed rolls adapted to clamp the record sheet against the platen, and including a front feed roll in front of the rear paper-table so located with reference to the pins that the second sheet gaged against the bite of the front feed roll will bring its first writing line in alinement with the writing line of the record sheet at the 115 pins, and a finger piece for effecting the withdrawal of said pins at will. 120

3. In a front-strike typewriting machine,

the combination with a revoluble platen, of a table above the printing point upon which a record sheet may be alined, a pair of disappearing pins mounted upon said table toward its lower edge and upon which openings at the writing lines of the record sheet are adapted to be centered, so that a selected writing line to receive the next printing is an aliquot number of line-spaces above 5 the printing point, feed rolls adapted to clamp the record sheet against the platen, and including a front feed roll so located with reference to the pins that a second sheet gaged against the bite of the front feed roll stands with its first writing line 10 in alinement with the writing line of the record sheet at the pins, a finger piece for effecting the withdrawal of said pins at will, and an extension of said table above 15 the pins, broad enough to flatten the record sheet to enable it to be alined thereupon.

4. In a front-strike typewriting machine, the combination with a revoluble platen, of a table above the printing point upon which

a record sheet may be alined, pins at said 25 table upon which openings at the writing lines of the record sheet are adapted to be centered, so that a selected writing line to receive the next printing is an aliquot number of line-spaces above the printing point, 30 releasable feed rolls adapted to clamp the record sheet against the platen, and a rear paper table for guiding the record sheet down to the feed rolls, but terminating so as to leave the space free in front of the feed 35 rolls to enable a second sheet to be inserted from the front and freely slipped down behind the record sheet and gaged against the bite of a front one of said feed rolls, said front feed roll so positioned that the second sheet when gaged thereagainst stands with its first writing line in alinement with the writing line of the record sheet at the 40 pins.
